UNITED STATES PATENT OFFICE

HERMANN WITTEK, OF HOLSTEIN, GERMANY, ASSIGNOR TO PAULINE STOCK, OF
ELKHART, INDIANA

LADDER

Application filed July 21, 1930, Serial No. 469,331, and in Germany July 25, 1929.

My invention relates to ladders of the folding type and has as its object the provision of such a ladder provided with an elevated well supported platform upon which the user 5 may stand, all with a view toward the provision of such a ladder which is light, simple and convenient, and which may be folded in compact form.

With this object in view my invention consists in certain features of novelty in the construction, combination, and arrangement of parts by which the said object is effected, all 10 as fully described with reference to the accompanying drawings and more particularly 15 pointed out in the appended claims.

In the said drawings—

Figure 1 is a perspective view of a ladder embodying my invention, with portions thereof broken away;

20 Figure 2 is a top plan view of the same;

Figure 3 is another perspective view of the ladder with the platform structure thereof folded, as hereinafter described; and,

25 Figure 4 is a side elevation of the ladder in folded condition.

Like characters of reference indicate like parts in the several views.

Referring to the drawings, 1 designates a ladder element of usual construction, and 30 2 designates a brace element of a construction similar to that of the ladder element. The ladder and brace elements have their upper ends pivoted together by means of suitable hinges 3, for movement to and from an extended self supporting position, as shown in Figures 1, 2 and 3, and a compact folded 35 position, as shown in Figure 4.

A platform 4 is provided with an intermediate cross member 5, the ends of which 40 are cylindrical, as designated at 6, and engage in cylindrical apertures 7 through the side members of the brace element 2 at upwardly disposed points thereon, see Figures 1 and 3, whereby the platform is intermediately pivoted on the brace element at an upwardly disposed point thereon for movement to and 45 from an extended horizontal position, as shown in Figures 1 and 2, and a folded position overlying the brace element, as shown 50 in Figure 3.

A strut element 8, of a construction similar to that of the ladder element 1, has its lower end pivotally connected to the lower end of the brace element 2 by means of suitable hinges 9 for movement to and from an extended position, as shown in Figures 1 and 65 2, and a folded position overlying the brace element, as shown in Figures 3 and 4.

When the strut element 8 and the platform 4 are in their extended positions, the strut element is engaged under the corresponding end of the platform to support the same while the other end of the platform engages downwardly upon the upper step 11 of the ladder element. See Figures 1 and 2.

60 The platform is preferably provided with adjacently spaced cross members 12 which engage on opposite sides of the step 11 to prevent displacement of the ladder element.

65 Hooks 13 are provided on opposite sides of the platform 4 which are engageable in eyes 14 on the upper end of the strut element to hold the same against a cross member 15 on the platform and to secure the strut element with the platform against pivotal movement of the strut element, these hooks being 70 releasable from these eyes to permit folding of the ladder.

75 It will be observed that when the ladder is set up with the platform extended, the platform is well supported and provides a safe and convenient place to stand on, all of the parts being secured in extended position.

The ladder may be used as an ordinary 80 step-ladder with the platform 4 and strut element 8 in their folded positions as shown in Figure 3.

85 When folded the ladder is quite compact as shown in Figure 4, and the sides of the ladder element are provided with hooks 16, which are engageable in eyes 17 on the sides of the strut element 8 to secure the ladder in folded position.

90 While I have herein shown and particularly described the preferred embodiment of my invention I do not wish to be limited to the precise details of construction shown as changes may readily be made without departing from the spirit of my invention, but having thus described my invention I claim as 95 100

new and desire to secure by Letters Patent the following:—

1. In a ladder the combination with ladder and brace elements pivotally secured together adjacent their upper ends, a platform intermediately pivoted on the brace element on an axis adjacent its upper end, and a strut element pivotally secured on said brace element adjacent its lower end and adapted to support the corresponding end of said platform in its extended position, the other end of said platform being engageable downwardly upon a step of the ladder element.
2. In a ladder the combination with ladder and brace elements pivotally secured together adjacent their upper ends, a platform intermediately pivoted on the brace element on an axis adjacent its upper end, a strut element pivotally secured on said brace element adjacent its lower end and engageable under the corresponding end of said platform in its extended position, the other end of said platform being engageable downwardly upon the upper step of the ladder element, and releasable means for securing said strut element engaged with said platform against pivotal movement of the strut element.
3. In a ladder the combination with ladder and brace elements pivotally secured together adjacent their upper ends, a platform intermediately pivoted on the brace element on an axis adjacent its upper end, a strut element pivotally secured on said brace element adjacent its lower end and engageable under the corresponding end of said platform in its extended position, the other end of said platform being engageable downwardly upon the upper step of the ladder element, releasable means for securing said strut element engaged with said platform against pivotal movement of the strut element, and means securing said ladder element against pivotal movement when said platform is engaged downwardly upon said upper step.
45. In witness whereof I affix my signature this 5th day of July, 1930.

HERMANN WITTEK.
